United States Patent

Des. 235,795

Patented July 8, 1975

235,795

TOY TRAIN TRACK

Teruo Matsumoto, Tokyo, Japan, assignor to Epoch Company, Ltd., Tokyo, Japan

Filed May 9, 1973, Ser. No. 358,643

Term of patent 14 years

Int. Cl. D21—01

U.S. Cl. D34—15 MM

FIG. 1

FIG. 2

FIG. 3

FIG. 1 is a top plan view of a toy train track embodying my new design;

FIG. 2 is an end elevation thereof; and

FIG. 3 is an enlarged, partial side elevation thereof. The bottom of the toy train track is substantially flat.

I claim:

The ornamental design for a toy train track, as shown and described.
